TIME STUDY DEVICE

Rudolf M. Richter, Brooklyn, N. Y.

Application August 22, 1939, Serial No. 291,320

3 Claims. (Cl. 235—86)

This invention relates to new and useful improvements in calculating devices and more particularly it pertains to a device for calculating so-called time studies.

A time study consists of determining the rate to be paid a workman on a piece work basis for a certain number of pieces of work or operations completed, based on the hourly or daily compensation of a workman.

10 In certain plants workmen are scaled according to their qualifications. For example, one group of workmen may be scaled at 40¢ per hour, one group at 50¢ and so on, and it is the purpose of the present invention to determine the price to be paid workmen of various groups on a piece work basis commensurate with their scaling upon the time basis.

It is a further object of the invention so to construct the device that it will be simple in its operation and of economical manufacture.

With the above and other objects in view, reference will be had to the accompanying drawing which illustrates one embodiment of the invention, and in which:

25 Figure 1 is a perspective view of a device constructed in accordance with the present invention,

Figure 2 is a plan view of the device on an enlarged scale with the cover removed therefrom,

30 Figure 3 is a transverse detail sectional view on an enlarged scale taken substantially on the line 3—3 of Figure 1,

Figure 4 is a transverse sectional view on an enlarged scale taken substantially on the line

35 4—4 of Figure 1, and;

Figure 5 is an inverted plan view of the cover plate of the housing.

Referring more specifically to the drawing, the reference numeral 10 designates a housing which is rectangular in form and which has a removable end wall 10' and a cover plate 11 removably held in position by means of screws or other suitable fastening means 12. The cover plate 11 has a window 14 which is rectangular in shape and through which is adapted to be exposed the indicia carried upon a web 15 of paper or other suitable material.

Mounted adjacent each side wall of the housing and carried by the end walls thereof, there is a shaft, these shafts being designated 16 and 17. The left hand end, in the drawing, of each shaft is mounted in a recess 18 and the other end of each shaft passes through an opening 19 in the removable end wall of the housing. Each shaft is preferably provided with a reduced por-

tion 20 upon which is secured an operating knob 21 by means of a pin or the like 22. Each of the shafts 16 and 17 is provided with a slot 23 which provides means for attaching the ends of the web to their respective shafts. Springs 60 5 are secured as at 61 to the housing and each of said springs has resilient legs 62 which engage the web as it is rolled upon the shafts, the springs exerting sufficient pressure to prevent accidental rotation of the shafts and the unwinding of the 10 web therefrom.

It will be noted that the web of paper is of sufficient width to engage the inner face of the end walls of the housing and to prevent longitudinal movement of the shafts, thus maintaining the shafts in proper operating position.

Intermediate of the two shafts 16 and 17, there are three idle rollers 24, 25 and 26. The rollers 24 and 26 are positioned closely adjacent the bottom wall 27 of the housing, while the roller 20 25 is mounted adjacent the cover plate 11 of the housing at a point immediately behind and in alignment with the window opening 14 thereof, as best illustrated in Figure 4. These idle rollers 24, 25 and 26 have reduced extensions 29 25 by which they are mounted in the end walls of the housing.

By an examination of Figure 4, it will be noted that the web 15 passes from the top side of the shaft 16, beneath the idle roller 24, over the idle 30 roller 25, beneath the idle roller 26 and under the shaft 17. By this arrangement of the web, the shafts 16 and 17 are operated in the same direction to wind the web thereon. For example, if the shaft 16 is turned in a clockwise direction, 35 the web will be wound upon the shaft 16 from the shaft 17 and similarly, if the shaft 17 is turned in a clockwise direction, the web will be wound thereon from the shaft 16.

As illustrated in Figure 5, the cover plate carries two bars 30 and 31 slidably mounted in suitable guides 32 upon the under side of said cover plate. The bar 31 carries a single pointer 33, the bar 30 carries a plurality of similar pointers, there being one pointer 34 and a plurality of 40 45 equally spaced pointers 35, 36, 37, 38, 39, 40 and 41 spaced from the pointer 34. The bars 30 and 31 are provided adjacent one end with a series of rack teeth 42 and mounted beneath the cover plate and meshing with the rack teeth 42 of the 50 bars 30 and 31, there is a gear 44. This gear is carried upon the inner end of a shaft 45 which is provided with an operating knob 46 mounted upon the shaft and positioned exteriorly of the cover plate 11 of the housing.

By this construction, if the shaft 45 is rotated the bars 30 and 31 will be reciprocated in opposite directions for a purpose to be hereinafter described.

- 5 The web carries certain indicia arranged in the form of columns, and adjacent the window 14 and mounted upon the outer face of the cover plate 11, there is a plate 50 which is divided into a plurality of areas 51, 52, 53, 54, 55, 56, 57, 58 and 59. These divisions are so arranged on the plate 50 with respect to the columns of indicia upon the web 15 as to register therewith. The division 51 carries the caption MIN. indicating "minutes." The division 52 carries the caption 10 PROD. indicating "production," while the remaining divisions 53 through 59 include figures indicating the hourly wage of groups of operators on a time basis according to their ratings as heretofore explained.
- 15 20 The left hand column on the web in the drawing indicates minutes and fractions thereof. The next column to the right indicates production and the succeeding columns indicate the pre-calculated price per hundred pieces to be paid 25 a workman depending upon the group of which he is a member.

I will now give an example setting forth the manner in which the device is used.

- Assuming that the article to be produced or the 30 operation to be performed consumes three minutes. In such a case the web is adjusted until the column indicating three minutes is visible through the window opening 14 thereof. The operating knob 46 of the shaft 45 is next grasped 35 and turned to reciprocate the bars 30 and 31 until the pointer 34 occupies a position between the three and the first zero to the right in which position the pointer is indicated in the drawing. Through the medium of the gear 44 and the rack 40 teeth 42 of the bars 30 and 31, the several pointers 34 through 41 are moved simultaneously with the moving of the pointer 34 to position between the three and the first zero to the right, to their proper positions with respect to the indicia in the 45 other columns upon the printed web 15.

In the drawing, the device is illustrated as adjusted to illustrate the problem above outlined and it will be noted that with the pointer 34 adjusted to position between the three and the 50 first zero on the right of the left hand column which indicates that the operation consumed three minutes, the pointer 33 of the bar 31 indicates that the production per hour would be eighteen. The remaining pointers 35 through 41 55 indicate the price per hundred pieces which the operator is to be paid according to the wage which he receives per hourly wage when computed upon a time basis. For example, if the operator's hourly wage is 40¢, he would receive \$2.218 per hundred pieces. If he were an operator whose hourly wage was 55¢, he would receive \$3.055 per hundred, or if he were an operator whose hourly wage was 72¢, he would receive \$4.00 per hundred pieces or operations.

- 65 It will be noted that there is an apparent discrepancy in the computation of the production with respect to the time. For example, if an operator takes three minutes to produce an operation or a piece, it would naturally be assumed that instead of eighteen pieces or operations per hour, he would complete twenty operations or pieces per hour. However, the indicia on the web is pre-calculated to automatically take care of a 70 ten per cent allowance for lost time allowed each 75

operator in a factory under general operating conditions.

From the foregoing it will be apparent that the present invention provides a device by which time studies can be more rapidly and more accurately computed than is possible with slide rules and similar devices at present employed, and while the invention has been described primarily as a time study device, it is obvious that by variations of the indicia employed upon the web and 10 upon the plate 50, the device may be adapted and operated to compute various problems other than time studies and it is to be understood, therefore, that the invention is not to be limited to time 15 study devices.

Having thus described the invention what is claimed, is:

1. A computing device comprising a housing having a window therein, a plate mounted upon the housing and extending parallel with one of the side edges of the window opening, said plate being divided into a plurality of areas each bearing an identifying indicia or caption, a printed web within the housing, the printed matter on said web being arranged in columns which coincide with the areas of the plate adjacent the window opening, means for moving said printed web across the window opening of the housing to expose sections of the columns of printed matter thereon through the window opening, a single pointer extending into the window opening from one side thereof and registering with one column of printed matter upon the printed web, a plurality of pointers extending into the window opening from the opposite side thereof, there being a pointer in said group for registration with each of the remaining columns of printed matter upon the printed web, and means for simultaneously moving said single pointer and said group of pointers in opposite directions relatively to their respective columns of printed matter upon the printed web.

2. A computing device comprising a housing having a window therein, a plate mounted upon the housing and extending parallel with one of the side edges of the window opening, said plate being divided into a plurality of areas each bearing an identifying indicia or caption, a printed web within the housing, the printed matter on said web being arranged in columns which coincide with the areas of the plate adjacent the window opening, means for moving said printed web across the window opening of the housing to expose sections of the columns of printed matter thereon through the window opening, a single pointer extending into the window opening from one side thereof, and registering with one column of printed matter upon the printed web, a plurality of pointers extending into the window opening from the opposite side thereof, there being a pointer in said group for registration with each of the remaining columns of printed matter upon the printed web, and means for simultaneously moving said single pointer and said group of pointers in opposite directions relatively to their respective columns of printed matter upon the printed web, said means comprising a pair of bars carried by the housing and arranged one upon each side of the window opening and upon which said pointers are mounted, and means for simultaneously reciprocating said bars in opposite directions.

3. A computing device comprising a housing having a window therein, a plate mounted upon the housing and extending parallel with one of

the side edges of the window opening, said plate being divided into a plurality of areas each bearing an identifying indicia or caption, a printed web within the housing, the printed matter on said web being arranged in columns which coincide with the areas of the plate adjacent the window opening, means for moving said printed web across the window opening of the housing to expose sections of the columns of printed matter thereon through the window opening, a single pointer extending into the window opening from one side thereof, and registering with one column of printed matter upon the printed web, a plurality of pointers extending into the window opening from the opposite side thereof, there

being a pointer in said group for registration with each of the remaining columns of printed matter upon the printed web, and means for simultaneously moving said single pointer and said group of pointers in opposite directions relatively to their respective columns of printed matter upon the printed web, said means comprising a pair of bars carried by the housing and arranged one upon each side of the window opening, and upon which said pointers are mounted, rack teeth 10 upon each of the said bars, a single gear interposed between said bars and operatively engaging the rack teeth of each, and means for rotating said gear.
